UNITED STATES PATENT OFFICE

EDWARD LESLIE GILBERT, OF FORT BAYARD, NEW MEXICO

SINGLE-SLEEVE-VALVE ENGINE

Application filed April 13, 1928. Serial No. 269,775.

This invention relates to an internal combustion engine, the general object of the invention being to provide the cylinders with sleeve valves, each having a pair of substantially triangular-shaped inlet ports and a pair of similar shaped outlet ports therein, with means for giving each sleeve a vertical and oscillatory movement so that the explosive mixture will be admitted to the cylinders in large quantities and the exhaust gases can freely escape from the cylinders, thereby increasing the efficiency of the engine.

Another object of the invention is to so form the operating parts of the sleeve valves that they have great strength and long life and they will operate with the minimum amount of noise.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is an elevation of the improved engine, showing the arrangement of ports in dotted lines.

Figure 2 is a section on line 2-2 of Figure 1.

Figure 3 is a section on line 3-3 of Figure 2.

Figure 4 is a section on line 4-4 of Figure 1.

Figure 5 is a view of one of the sleeve valves, with parts broken away to show the ports on the opposite side thereof.

Figure 6 is a section on line 6-6 of Figure 5.

Figure 7 is a section on line 7-7 of Figure 5.

In these views, the numeral 1 indicates the cylinder block which is formed with the cylinders 2, the head of the block being indicated at 3 and this head is provided with the depending portions 4 which extend into the

cylinders 2 and are bored, as at 5, to receive a spark plug 6. As shown, each depending part 4 is spaced from the upper end of each cylinder to form an annular space which receives the upper end of the sleeve valve 7.

The crank case is shown at 8 and the crank shaft at 9, this crank shaft being connected in the usual manner with the pistons 10 by the connecting rods 11, the pistons reciprocating in the sleeve valves. Each valve is of cylindrical shape with both ends open and the lower end of each sleeve is formed with an annular groove 12 to receive a collar 13 which is rotatably mounted in the groove.

A shaft 14 is journaled in the crank case at one side thereof and a shaft 15 is journaled in the other side of the crank case. These shafts are driven from the crank shaft by the sprockets and chains, shown generally at 16. The shaft 14 carries a number of eccentrics 17, one for each cylinder, and the eccentric strap 18 of each eccentric is connected by a rod 19 with the collar 13 of each sleeve. Each connecting rod 19 is held against side movement by a bracket 20 attached to the top of the crank case and depending therefrom and having its forked end 21, which extends at right angles from the bracket, receiving the rod between the prongs thereof.

A plurality of parts of eccentrics 22 are carried by the shaft 15, a pair for each sleeve, and the eccentric straps 23 of each pair of eccentrics are connected by the rods 24 with the lower part of each sleeve through means of the ball and socket connection shown generally at 25. As shown, one connecting rod of each pair is connected to one side of the sleeve and the other rod of each pair is connected to the opposite side of each sleeve. The eccentrics of each pair are oppositely arranged, as shown in Figure 3, so that as one rod is moving outwardly, the other rod is moving inwardly so that both rods tend to oscillate the sleeve as the shaft 15 is rotated.

The upper part of each sleeve is formed with a pair of inlet ports 26 on one side of the sleeve and with a pair of outlet ports 27 at the opposite side of the sleeve, the ports 27 being located in a lower plane than the

ports 26, with each port 27 arranged to one side of the vertical plane of each port 26, as shown in Figure 5. All the ports are of substantially triangular shape in cross section. Each cylinder is formed with a pair of inlet ports 28 and a pair of outlet ports 29. These ports are also of substantially triangular shape.

Guides 30 are also provided for the connecting rods 24 for preventing side movement of these rods.

From the foregoing it will be seen that the sleeve valves are given a reciprocatory movement by the shaft 14, the eccentric 17 and the connecting rods 19 and at the same time are given an oscillatory movement by means of the shaft 15, the eccentrics 22 and the connecting rods 24, the sleeve turning in the collar 13.

Thus the ports 26 and 27 are each moved in a substantially elliptical path so that each set of ports will come into register with the inlet or exhaust ports of each cylinder as the ports move over this path. Due to the shape of the ports, a large amount of combustible mixture will enter each cylinder and the exhaust gases can freely escape from the cylinders during the exhaust strokes of the pistons.

It is thought from the foregoing description that the advantages and novel features of my invention will be readily apparent.

It is to be understood that I may make changes in the construction and in the combination and arrangement of the several parts, provided that such changes fall within the scope of the appended claim.

What I claim is:—

An internal combustion motor comprising a cylinder block, a head fitting thereon and having depending portions extending into the cylinders and spaced from the internal walls of the cylinders, a sleeve valve arranged in each cylinder with its upper end entering the space formed between the depending part of the head and the upper end of the cylinder, a crank case connected with the block, a crank shaft in the case, a piston slidably arranged in each sleeve valve, a rod connecting each piston with the crank shaft, a pair of shafts journaled in the crank case, means for connecting the shafts with the crank shaft, eccentrics on the shafts, rods connected with the eccentrics on one shaft, collars rotatably arranged on the sleeve valves and pivoted to said rods, projections on the lower end of each sleeve at opposite sides thereof, each projection having a rounded head, a pair of connecting rods having sockets at their inner ends receiving the heads of the projections on each sleeve, the outer ends of each pair of rods being connected with a pair of the eccentrics on the second shaft, a depending member in the crank case having a forked rightangular end, the prongs of which engage each rod which is pivotally connected

with the collar for preventing side movement of said rod and a second forked member depending from a part of the crank case for engaging each rod connected with a projection on the sleeve for preventing side movement of said rod.

In testimony whereof I affix my signature.

EDWARD LESLIE GILBERT.
